UNITED STATES PATENT OFFICE.

JAMES R. MOFFATT AND RALPH S. KELSO, OF CHICAGO, ILLINOIS, ASSIGNORS TO UNION SPECIAL MACHINE COMPANY, OF CHICAGO, ILLINOIS, A CORPORATION OF ILLINOIS.

THREAD-NIPPER.

1,312,799.

Specification of Letters Patent. Patented Aug. 12, 1919.

Application filed September 26, 1917. Serial No. 193,362.

To all whom it may concern:

Be it known that we, JAMES R. MOFFATT and RALPH S. KELSO, citizens of the United States, residing at Chicago, in the county of Cook, State of Illinois, have invented certain new and useful Improvements in Thread-Nippers, of which the following is a description, reference being had to the accompanying drawing and to the figures of reference marked thereon.

The invention relates to an improvement in a device for controlling a plurality of needle threads of a multiple needle sewing machine.

15 The invention is broadly directed to the same subject matter disclosed in the patent to D. W. Corey, 1041597, patented October 15, 1912, and embodies specific improvements to the patent granted to J. R. Moffatt, 20 1139793 patented May 18, 1915.

One of the objects of the present invention is to provide a thread nipping or clamping device which includes a plurality of clamping disks which are normally pressed 25 apart to permit the free passage of the threads between the respective disks and to provide thread guides for directing the threads across the centers of said disks, whereby said disks when urged together, 30 will nip the threads with equal force.

Another object of the invention is to provide a holder for the disks which is substantially self-clearing of the lint which would otherwise accumulate therein and interfere 35 with the proper working of the device.

These and other objects will in part be obvious and will in part be hereinafter more fully disclosed.

In the drawings, which show by way of 40 illustration one embodiment of the invention,

Figure 1 is a front elevation of a sewing machine equipped with our invention;

Fig. 2 is a top plan view thereof;

45 Fig. 3 is an enlarged elevation, the holder for the disks being shown in section;

Fig. 4 is a cross sectional view thereof; and

50 Fig. 5 is a view showing in perspective the various parts of the thread nipping device.

In carrying out our invention, the needle bar which carries a plurality of needles, is reciprocated by a lever, and this lever during each reciprocation, actuates a multiple 55 thread nipper to nip the threads during a

portion of the time the needle eyes are below the fabric so as to insure the proper setting of the stitches by certain thread controlling mechanism, and thereby prevent any one or more threads being pulled through the nippers from the supply. This thread nipper includes a holder into one end of which the thread nipping disks are inserted and arranged in parallel relation. The holder is formed with thread guides which are so arranged that the respective threads are led between corresponding pairs of disks and across the axis thereof. A lever, fulcrumed on the holder, is actuated by the needle lever to force the disks against a variable tension 70 spring, and thereby simultaneously clamp or nip each of the several threads. The lever carries a disk which has bodily movement toward and from the floating disks, and as a result, when the lever is moved in a 75 direction for nipping the threads, all of said disks are moved and their parallelism is maintained, thus insuring positive action on all the threads by said disks. Directly under the disks, the holder is formed with 80 an opening of a size sufficient to readily permit the thread lint passing outwardly from the holder, and thereby insure a freedom of action for the disks.

Referring more in detail to the drawings, 85 we have shown our improvements as applied to a sewing machine having a supporting bed 1 carrying an overhanging arm 2 in which a needle bar 3 reciprocates. This needle bar is provided, as herein shown, 90 with a plurality of needles 4. The needle bar is reciprocated by a needle lever 5 which is connected thereto by a link 6. This needle lever is oscillated by an eccentric on the main shaft. Coöperating with the respective needles are loopers 7 which are oscillated by a link 9 pivotally connected to the needle lever extension 10. Suitably mounted on the bed 1 is a work support 11 having suitable feed slots for the reception 100 of a feed dog 12 of the four-motion type which is operated in the usual manner. Coöperating with the work support is a presser foot 13 carried by a presser bar 14 which is slidably mounted in suitable bearings in the 105 overhanging arm 2. This foot is held against the fabric being sewed by a spring 15, and moves up and down with the feed dog and also with fabrics of different thicknesses.

The needle threads are led from the supply through individual tensions 16 mounted on the overhanging arm, through suitable guides 17 on the overhanging arm, 5 thence through the eyelet 18 on the controlling lever 19, thence through the thread guide 20 mounted on the needle lever, and finally through the thread guide 21 mounted on the needle bar 3 to the respective needles.

10 The controlling lever 19 is fulcrumed on the overhanging arm and engages a fixed segment 22 adjustably mounted on the presser bar. The movement of the eyelet 18, relative to a line passing through the thread guides 17 and 20, determines the amount of thread pulled thereby through the tensions from the supply, and consequently determines the amount of thread employed in the successive stitches when sewing upon ordinary materials. The above parts are all of well known construction.

It sometimes happens, when sewing certain materials, such as leather, that the needle thread will, when said needle is passing downwardly, become pinched between the needle and the side of the opening formed thereby, and, if the resistance is greater at this point than at the tension, an excessive amount of thread will be pulled through the tension. This excess thread will of course be embodied in the succeeding stitch, and this stitch will consequently be looser than the others.

Secured to the inner face of the overhanging arm 2 is a supporting plate 23 of the thread nipper, and fixed to this plate is a forwardly extending tubular holder 24 for a series of clamping disks 25 which are arranged in parallel relation. The inner disk 35 is secured to the upper end of an actuating lever 26 which is fulcrumed in the plate 23. The outer disk carries a fixed pin 27 which extends forwardly through an opening 28 formed in a stop plug 29. This plug is adjustably secured in the outer end of the holder by a screw 30. Disposed between the outer disk 25 and said stop plug 29, is a coil spring 31 which surrounds the pin 27. The opening 28 forms a guide for the pin 27 and thereby maintains the attached disk in a vertical plane. Lock nuts 32 are secured to the outer end of the pin 27 and bear against the stop plug 29 to limit the inward movement of the inner disk through the action of the spring 31. The upper portion of the holder is recessed as at 33 and formed in the opposite walls thereof are downwardly extending thread slots 34 which terminate in thread guides 35. These guides are arranged in pairs for the respective threads and are disposed in a horizontal plane containing the major axis of the holder to cause the threads to pass across the axes of said disks. The slots 34 permit the holder to be 60 readily threaded.

Fixed to the needle lever 5, is a plate 36 and adjustably secured to the lower end thereof is a shoe 37 which is adapted on downward movement of the lever, to engage a block 38 carried on the lower end of the 70 nipper lever 26 and thereby actuate the latter.

In operation, as the needle lever is reaching the lower end of its stroke, the nipper lever 26 will be oscillated, and the disks 25 75 will be moved forwardly and against the spring 31, said spring being thereby compressed and the threads nipped and held nipped until the needles have started to rise and the needle thread loops have been drawn 80 up. The nipper lever 26 will then be released and the disks 25 will then permit of threads being pulled from the supply by the controlling mechanism. By means of the adjustable stop block 29, the clamping action of the disks on the threads may be readily varied to suit conditions.

Directly below the disks, the holder is formed with an opening 39 of a size sufficient to permit the lint passing out of the 90 holder and thereby insure the proper working of the nipping device.

Having thus described our invention what we claim as new and desire to secure by Letters Patent, is:—

1. In a multiple thread nipping device, the combination with a tubular holder, of a plurality of clamping disks loosely mounted therein and supported thereby, a tension spring disposed within said holder and located at one end thereof, said holder being provided with means for leading the threads between the several disks, and means for moving said disks against the spring for clamping said threads. 100

2. In a multiple thread nipping device, the combination with a tubular holder, of a plurality of clamping disks loosely supported therein, a tension spring disposed within said holder and located at one end thereof, said holder being provided with means for leading the threads between the several disks, and means for moving said disks against the spring for clamping said threads, said means including an actuating lever having connection with the disk farthest removed from said spring. 110

3. In a multiple thread nipping device, the combination with a tubular holder, a stop plug secured within one end of the holder, a plurality of clamping disks supported within said holder, a tension spring located within the holder between said stop plug and said disks, means for leading the threads between the several disks, and means 120 for moving said disks against the spring for clamping said threads.

4. In a multiple thread nipping device, the combination with a tubular holder, a stop plug secured within one end of the 130

holder, a plurality of clamping disks supported within said holder, a tension spring located within the holder between said stop plug and said disks, means for leading the threads between the several disks, and means for moving said disks against the spring for clamping said threads, and a guide pin fixed to the end disk and extending through said stop plug.

- 5 10 5. In a multiple thread nipping device, the combination with a tubular holder, of a plurality of clamping disks loosely mounted therein and supported thereby, a tension spring located within the holder and engaging said disks, said holder being horizontally disposed and having formed in its under face openings for the egress of lint.
- 15 6. In a multiple thread nipping device,

the combination with a horizontally disposed tubular holder, of a plurality of 20 clamping disks loosely mounted therein and supported thereby, means for guiding the several threads between the respective disks and across the axes thereof, spring means for forcing the disks against an abutment 25 for clamping the threads, and means for moving the abutment to release the threads from tension.

In testimony whereof, we affix our signatures, in the presence of two witnesses.
